FLANGE WRENCH

Alexander W. Thom, Brooklyn, and Walter
Fryer, New York, N. Y.

Application January 21, 1944, Serial No. 519,124

1 Claim. (Cl. 81—90)

This invention relates to flange wrenches, and aims to provide a simple, practical and efficient tool adapted to be used in combination with one or more specially constructed pins which are insertable into the bolt holes of the flange, to turn the flange so as to screw it on or off a pipe end or other threaded article. The problem of tightening or loosening such a flange is often a very difficult one because of the tendency of the usual types of wrenches to slip on the flange surfaces because of the relatively large amount of torque needed to turn the flange, and it is the object of this invention to provide a wrench which overcomes that difficulty and is always ready to be applied for the purpose stated.

The above and other objects will become apparent in the description below, wherein characters of reference refer to like-numbered parts in the accompanying drawing. It is to be noted that the drawing is intended to serve the purpose of illustration only, and it is neither intended nor desired to limit the invention to any or all of the details illustrated excepting insofar as they may be essential to the invention.

Referring briefly to the drawing,

Fig. 1 is a side elevational view, partly in section and with parts broken away, showing the application of the wrench to a flange.

Fig. 2 is a plan view of the wrench in laid out condition.

Fig. 3 is a cross-sectional view taken on the line 3—3 of Fig. 1.

Fig. 4 is an end elevational view of the wrench.

Fig. 5 is a side elevational view of one of the special pins adapted for use with the wrench.

Fig. 6 is an end view of Fig. 5.

Fig. 7 is a fragmentary perspective view pivoted yoke member of the wrench.

Referring in detail to the drawing, the numeral 10 indicates an elongated rod which may be provided with a handle 11 at one end, the other end being formed into a fork 12 having a bolt 13 supported therein.

A yoke 14 comprising the two spaced parallel, flat arms 15, is provided with a reduced and rounded neck extension 16 having an opening 17 therethrough. The neck 16 registers within the fork 12 with the bolt 13 passing through the opening 17, whereby the yoke 14 is pivotally suspended from the rod 10.

Each arm 15 is provided with spaced recesses cut into that edge thereof which faces toward the rod 10 when the latter is held horizontal and the yoke is freely suspended therefrom; thus a plurality of spaced rows of horizontally aligned

recesses are provided in the yoke. The recesses 18 are cut relatively deeply in a longitudinal direction toward the free ends of the arms 15, and the bases of the recesses, thus formed, are rounded, as shown at 19. Upwardly projecting hooks 20 are thus formed adjacent each recess base 19.

To illustrate the application of the device, a flange, such as a pipe terminal flange, is shown in end view at 21, and it is seen in Fig. 1 that the lower edge of the rod 10 is provided with an arcuately dished out cut-out 22 having the opposed parallel walls 23 and having the roof of the cut-out provided with serrations or teeth 24. The radius of curvature of the serrated roof 24 is similar to that of the flange 21.

Such flanges are commonly provided with spaced peripheral bolt holes 25, and one or more cylindrical pins 26 are provided to be inserted into the holes 25 to provide a grip for the wrench. These pins comprise a cylindrical body 27 having peripheral grooves 28 formed near the ends thereof, thus providing spaced spindles 29 at the ends of the central body portion 27 and provided on their extremities with heads 30. The length of the central body 27 is equal to the distance between the yoke arms 15, and the length of each spindle portion 29 is equal, substantially, to the thickness of the yoke arms.

30 To use the wrench, one or more pins 26 are inserted into the bolt holes 25 of the flange, with the central body 27 supported in the bolt hole and with the spindles 29 and heads 30 protruding from the ends of the hole. The yoke 14 is then brought into the position shown in Fig. 1, with the spindles 29 registering in the bases 19 of the recesses 18, as shown in Fig. 7. The rod 10 is then positioned as shown in Fig. 1, with the flange 21 entering into and registering in the cut-out 22.

40 It is obvious that downward pressure applied to the handle 11 will loosen the flange to turn it in a counterclockwise direction. The manner of applying the tool to cause turning of the flange in the opposite direction is obvious. The serrated roof 24 serves as an added means for locking the tool and flange together, as is also obvious, although the tool will also function even if the radius of curvature of the flange is greater or

45 smaller than that of the arcuate cut-out 22. The shackle-like engagement between the pins 26 and the yoke prevent any possibility of the pins falling out or loosening out of position.

50 A set of pins 26 of varying diameters would be provided with each tool, so that the proper pin

may always be available for any common diameter of bolt hole apt to be met with.

Obviously, modifications in form and structure may be made without departing from the spirit and scope of the invention.

We claim:

A tool for gripping a disc-like article having a hole therethrough near the periphery thereof, comprising a rod having a yoke suspended from one end thereof, the arms of said yoke having spaced aligned recesses cut into the edges thereof on one side of said yoke, said recesses having longitudinal extensions in a direction toward the

free end of the arms, said recess extensions being rounded at their bases, and a pin insertible into said hole having a central body provided with spindles projecting from the ends thereof and having heads on the ends of said spindles, said yoke being applied to said article with said spindles registering in said recess terminals of the aligned recesses of one of said rows of recesses, said heads thereby restraining said pins from slipping out of said recesses.
